PLATFORM TYPE SHOE, SLIPPER, OR THE
LIKE AND METHOD OF MAKING SAME

Anthony Orlando, Bronx, N. Y.

Application September 19, 1946, Serial No. 698,068

14 Claims. (Cl. 36—19.5)

1

This invention relates to shoes, slippers and other footwear and to methods for making them and more particularly to platform shoes or slippers and shoes or slippers so constructed that their construction is strong and sightly and their method of making on a sewing machine facilitated though it is noted that in some of the claims the invention is not limited to parts secured together by stitches, or to platform shoes.

One object of the invention is to provide improved footwear of this kind so constructed that parts to be secured together are easily placed between the pressure foot and feed bed of an ordinary single needle straight stitch or by a zig-zag stitch sewing machine.

Other objects of the invention are to provide an improved construction of this kind which enables the shoe to be lasted before applying the platform and outsole and to provide a strong stitch where great strain comes.

Additional objects of the invention are to effect simplicity and efficiency in such methods and footwear and to provide an extremely simple shoe or slipper of this kind which is economical, durable, sightly and reliable in use and economical to manufacture.

Still other objects of the invention will appear as the description proceeds; and while herein details of the footwear and method steps and their order are described in the specification and some of the claims, the invention as described in the broader claims is not limited to these, and many and various changes may be made without departing from the scope of the invention as claimed in the broader claims.

The inventive features for the accomplishment of these and other objects are shown herein in connection with several forms of slipper or shoe each of which briefly stated includes an insole superposed on a platform, and a wrapper having its upper margin disposed adjacent to the insole with the edge of said upper margin inset from the edge of the platform, the wrapper having its lower margin drawn downwardly around the edge face of the platform and turned inwardly and secured to the margin of the lower face of the platform. A foxing strip or strips forming the lower portion of the upper has an inner margin superposed upon the upper margin of the wrapper; and stitches passing through the insole, the lower margin of the foxing strip and the upper margin of the wrapper for securing the margins in superposed position and to hold them to the insole.

The foxing strip and an upper member hav-

2

ing its lower edge secured by lacing, padding-machine stitching or other means to the upper edge of the foxing strip cooperate to form the shoe or slipper upper; and an outsole is secured to the lower face of the platform and the lower face of the inturned part of the wrapper.

My improved methods of making footwear include superposing the inner edge of a foxing blank upon the inner edge of a wrapper blank and stitching the superposed edges to the margin of an insole and securing, to the outer edge of the foxing blank, the lower edges of blanks cooperating with the foxing blank to form uppers, after which the footwear may be lasted. A sole-shaped platform is secured to the lower face of the insole, and the lower margin of the wrapper is drawn around the edge of the platform and secured to the bottom face of the platform, after which an outsole is secured to the bottom face of the platform and said lower margin of the wrapper.

Any suitable or usual leather, skin or other material or contrasting materials may be used for making the wrappers, the upper part of the shoe or slipper uppers and the foxing strip. The construction and method are particularly suitable for making the foxing strip, upper member and sock lining of sheep skin shearling. The wrapper may be made of any suitable leather or material and the platform, outsole and insole and sock lining may also be made of any usual or suitable material.

While particular advantages result from the stitching stated above, it is noted that substitution of cementing or other securing methods, or vice versa, may be made when conditions seem desirable.

In the accompanying drawing showing, by way of example, several of many possible embodiments of the invention,

Fig. 1 shows a side elevation of a slipper or shoe as it appears when made by any of the several methods or constructions herein;

Fig. 2 is a sectional view of one form of construction of the invention with a last therein, the section being taken in a transverse plane located as indicated by the line 2—2 of Fig. 1; and

Figs. 3, 4 and 5 respectively show similarly located sections of other forms of the invention, Figs. 4 and 5 being fragmentary;

Figs. 6 and 7 are sectional views partly in elevation showing a step in the method of making the shoes of Figs. 2 and 3 respectively.

My improved footwear as shown in Figs. 1 and 2 comprises a platform 10 of cork, felt or other material on which is superposed an insole 11

of leather, fabric or the like having its margin 12 turned down and disposed against the edge face of the platform. A sock-lining or sole-shaped member 13 is secured by cement or stitches 14 or both on the insole with its edge inset from the edges of the platform.

A platform wrapper 15 having its upper margin 16 butting the edge face of the sock lining has its lower part 17 drawn downwardly around the margin of the insole and secured to the lower face of the margin of the platform. The margin 12 may be cemented to the wrapper and the edge face of the platform if desired. A foxing or other strip 18 has its inner margin superposed upon the upper margin 16 of the wrapper and butting against the edge face of the sock lining 13; and a line of stitches 20 passes through said insole 11, the lower margin of the foxing strip, and the upper margin of the wrapper for securing them all strongly together.

Upper members 21, 21' have their lower margins secured to the upper edge of the foxing strip by means of laces 22, contrasting or otherwise, as in Figs. 1 and 2 or by padding machine stitches as at 22a in Fig. 3, or by other means to form the shoe or slipper uppers; and an outsole 24 is secured to the lower face of the platform and the lower face of the lower part of the wrapper.

My improved method of making the footwear of Figs. 1 and 2 includes placing a sock-lining 13 (Figs. 2 and 6) of approximately sole shape, and of less than sole length and width on a similarly shaped insole 11 of greater than sole width and length, leaving an exposed upper face of the margin 12 of the insole, and securing the edges of the thus placed sock-lining to the insole by stitches 14 or by cement or both. The inner edges of a foxing blank 18 are superposed upon the inner edge 16 of a wrapper blank and placed in abutment against the edges of the sock-lining as a guide, the margins being placed between the pressure-foot 25 (Fig. 6) and feed bed 26 and dog 27 of an ordinary single needle straight stitch sewing machine after which the margins are stitched together, the line of stitches 20 passing through said blanks 15, 18 and the insole 11, the disposition of the blanks allowing entirely free access of the pressure-foot and feed bed and dog to the blanks and insole.

The outer edge of the foxing blank 18 is then secured by laces 22 or stitches to the lower edges of blanks 21, 21' cooperating with the foxing blank to form the shoe or slipper uppers, for lasting by inserting a last 30 in the uppers against a sock-lining 13.

The sole-shaped platform 10 is then cemented to the lower face of the insole with the margins of the insole projecting substantially uniformly beyond the platform. Then the wrapper 15 is drawn downwardly to force the insole margin 12 against the edge face of the platform, and the lower margin of the wrapper 17 is drawn under the platform as in Fig. 2 and cemented to the lower face of the platform after which the outsole 24 is cemented to the lower face of the platform and said lower margin 17 of the wrapper.

The stitches 20 form an extra strong securing means for holding the strip 18 and the wrapper margin 16 in place.

My improved footwear as shown in Fig. 3 comprises a platform 10 on which is superposed an insole 11a having its edges inset from the edges of the platform. A wrapper 15a having its upper margin 16 abutting the edge face of the insole 11a has its lower part 17 disposed downwardly

around the edge face of the platform and turned inwardly and cemented to the margin of the lower face of the platform 10. A foxing strip 18 has its inner margin superposed upon the upper margin of the insole. Zig-zag stitches 14a, 20a comprise stitches 14a passing through the edge of the insole, and stitches 20a passing through the lower margin of the foxing strip and upper margin of the wrapper, thus securing these margins in superposed relation. The threads 31 of the zig-zag stitches connect the stitches 14a, 20a together and hold said superposed margins of the foxing strip and the wrapper against the edge of the insole.

15 A sock lining 13a secured by cement, stitches 32 or other means on the insole and over said zig-zag stitches 14a, 20a and an upper member 21 has its lower edge secured by padding machine stitches 22a or other means to the upper edge of the foxing strip 18. An outsole 24 is secured to the lower face of the platform and the lower face of the inturned part 17 of the wrapper.

My improved method of making the footwear of Fig. 3 includes the steps of superposing the inner edge of a foxing blank 18 upon the inner edge of the margin 16 of a wrapper blank 15a disposing said superposed edges in abutment to the edge face of an insole 11a of approximately sole shape, and of less than sole length and width with said blanks substantially in the plane of the insole as in Fig. 7 and placing the abutting edges between the pressure-foot 25a, feed dog 27a and feed plate 26a of a zig-zag sewing machine, and securing all of said edges together by means of zig-zag stitches, one line of stitches 20a passing through said blanks, the other line 14a passing through the insole. Then the sock lining 13a may be secured over the insole and the zig-zag stitches by cement or by stitches 32 or other means. The stitches 32 may be placed through or at either side of the zig-zag stitches.

Next the outer edge of the foxing blank 18 may be secured to the lower edges of blanks 21, 21' cooperating with the foxing blank to form uppers; 45 after which the shoe or slipper may be lasted by inserting a last 30 in the uppers against the sock-lining. This lasting holds the assembled parts for cementing a sole-shaped platform 10 to the lower face of the insole and drawing the lower margin 17 of the wrapper under the platform and cementing it to the lower face of the margin of the platform, after which an outsole 24 may be cemented to the lower face of the platform and said lower margin of the wrapper.

55 The form of invention of Fig. 4 is similar to that of Fig. 2, except that the member 13b corresponding to the sock-lining serves as an inner lining resting on the insole 11, and a sock-lining 13c cemented, stitched or otherwise secured thereon is disposed over the stitches 14, 20 securing the inner lining 13b, insole 11, and the wrapper 15 and strip 18 together. The sock-lining 13c may be cemented in place or stitched in place by a line of stitches 32b placed in any convenient location or at the extreme marginal portion as shown.

The form of invention of Fig. 5 is similar to that of Fig. 4, except that the inner lining 13b of Fig. 4 is omitted and the sock-lining 13c is disposed against the intra-marginal part of the insole 11 of the foxing strip 18. It may be cemented in place or secured by suitably placed stitches 32c.

Various combinations of the features of Figs. 2 to 5 may be made if desired.

The method of making the form of invention

of Fig. 4, except for the sock lining 13c, is the same as described of Figs. 2 and 6, and the method of adding the sock lining 13c is the same as adding the sock lining 13a of Figs. 3 and 7.

The method of making the form of invention 5 of Fig. 5, is the same as that of Fig. 4 except that the inner lining 13b is omitted.

The invention claimed is:

1. Footwear which comprises a platform; a sole-shaped member superposed on the platform; a wrapper having its upper margin adjacent to said member with the edge of said margin inset from the edge of the platform, the wrapper having its lower margin drawn downwardly around the edge face of the platform and turned inwardly and secured to the margin of the lower face of the platform; an outsole secured to the lower face of the platform and the lower face of the in-turned part of the wrapper; a foxing strip having its inner margin disposed above the level of the bottom face of said member and superposed upon the upper margin of the wrapper; stitches engaging the platform passing through said member, the lower margin of the foxing strip and the upper margin of the wrapper thereon for securing the margins in superposed position and to hold them to the insole; and an upper member having its lower edge secured to the upper edge of the foxing strip and cooperating therewith to form uppers.

2. Footwear which comprises a platform; a sole-shaped member disposed over the platform and having its edges inset from the edges of the platform; a wrapper having its upper margins butting the edge of said member and its lower part drawn downwardly around the edge face of the platform and turned inwardly and secured to the margin of the lower face of the platform; an outsole secured to the lower face of the platform and the lower face of the in-turned part of the wrapper; a foxing strip having its inner margin superposed upon the upper margin of the wrapper against the edge of the insole; lines of means including stitches having one line of the stitches passing through the edge of the insole, and the other line of the stitches passing through the lower margin of the foxing strip and the upper margin of the wrapper thereon for securing the margins in superposed position and to hold them together and to the edge of the insole; an additional member secured over the first-named member secured on the insole and over said stitches; and an upper vamp member having its lower edge secured to the upper edge of the foxing strip.

3. Footwear which comprises a platform; an inner member disposed over the platform with its edges inset from the edges of the platform; a wrapper having its upper margin butting the edge of said inner member and its lower part drawn downwardly around the edge of the platform and secured to the lower face of the margin of the platform; an outsole secured to the lower face of the platform and the lower part of the wrapper; a foxing strip having its inner margin superposed upon the upper margin of the wrapper against the edge of the inner member; a line of stitches passing through the margin of the inner member, the lower margin of the foxing strip and the upper margin of the wrapper for securing said margins together; a sock lining disposed over the inner member over said stitches; and an upper member having its lower edge secured to the upper edge of the foxing strip.

4. Footwear which comprises a platform; an

insole superposed on the platform and having its margin downturned and disposed against the edge face of the platform; an inner lining on the insole with its edges inset from the edges of the platform; a wrapper having its upper margin on the margin of the insole and its lower part drawn downwardly around the margin of the insole and secured to the lower face of the margin of the platform; an outsole secured to the lower face of the platform and the lower part of the wrapper; a foxing strip having its inner margin superposed upon the upper margin of the wrapper; a line of stitches passing through said insole, the lower margin of the foxing strip, and the upper margin of the wrapper for securing them together; upper members having their lower edges secured to the upper edge of the foxing strip; and a sock lining disposed over the platform and said margins.

5. Footwear which comprises a platform; an insole superposed on the platform; a wrapper having its upper margin disposed over the insole and its lower part drawn downwardly around the margin of the insole and secured to the lower face of the margin of the platform; an outsole secured to the lower face of the platform and the lower part of the wrapper; a foxing strip having its inner margin superposed upon the upper margin of the wrapper; stitches passing through the lower margin of the foxing strip, the upper margin of the wrapper and the insole for securing the margins in superposed position and to hold them together and to the insole; a sock lining disposed over the insole and over said stitches; stitches passing through the sock lining, said strip, said wrapper and said insole; and an upper member having its lower edge secured to the upper edge of the foxing strip.

6. Footwear which comprises a platform; an insole superposed on the platform and having its margin downturned and disposed against the edge face of the platform; a wrapper having its upper margin disposed on the insole over the margin of the platform, and its lower part drawn downwardly around the margin of the insole and secured to the lower face of the margin of the platform; an outsole secured to the lower face of the margin of the platform; a foxing strip having its inner margin superposed upon the upper margin of the wrapper against the edge of the sock lining; a line of stitches passing through the lower margin of the foxing strip, the upper margin of the wrapper thereon and the insole for securing said margins in superposed position to hold them together and on the insole; a sock lining having its edges disposed over said stitches; and an upper member having its lower edge secured to the upper edge of the foxing strip.

7. Footwear which comprises a platform having edge faces; a sole-shaped member superposed on and extending entirely across the middle part of the platform, the extreme edge of the member engaging the platform; a wrapper having its upper margin adjacent to the sole-shaped member with the edge of said margin inset from the edge of the platform, the wrapper having its lower margin drawn forwardly around the edge face of the platform and turned inwardly and secured to the margin of the lower face of the platform; a foxing strip having its inner margin superposed upon the upper margin and edge of the wrapper against the edge of the sole-shaped member; stitches passing through said member, the lower margin of the foxing strip, and the upper margin of the wrapper for

securing such margins in superposed position and to hold them to the member; an outsole secured to the lower face of the platform and the lower margin of the wrapper; and an upper member having its lower edge secured to the upper edge of the foxing strip.

8. Footwear which comprises a thick platform having edge faces; a sole-shaped member superposed on and extending entirely across the middle part of the platform, the extreme edge of the member engaging the platform; a wrapper having its upper margin adjacent to the sole-shaped member with the edge of said margin inset from the edge of the platform a distance approximately as great as the thickness of the platform, the wrapper having its lower margin drawn forwardly around the edge face of the platform and turned inwardly and secured to the margin of the lower face of the platform; an outsole secured to the lower face of the platform and lower margin of the wrapper; a foxing strip having its inner margin superposed upon the upper margin and edge of the wrapper; stitches passing through said member, the lower margin of the foxing strip, and the upper margin of the wrapper for securing such margins in superposed position and to hold them to the member; the lower part of the stitches and the edge of the sole-shaped member engaging the platform; and an upper member having its lower edge secured to the upper edge of the foxing strip.

9. Footwear which comprises a platform having edge faces; an insole stitched and superposed on and extending entirely across the platform; a sole-shaped member disposed entirely across the intramarginal part of the insole and having its edges inset from the edges of the platform; a wrapper having the edges of its upper margin abutting the edge face of said sole-shaped member, the wrapper having its lower margin drawn downwardly around the edge face of the platform and turned inwardly and secured to the lower face of the platform; a foxing strip having its inner margin superposed upon the upper margin of the wrapper and its lower edge abutting the edge face of the sole-shaped member; stitches passing through the insole, the lower margin of the foxing strip, the upper margin of the wrapper for securing said margins in superposed position and to hold them to the insole; and an upper member having its lower part secured to the upper margin of said strip.

10. Footwear which comprises a platform having edge faces; an insole stitched and superposed on and extending entirely across the platform and having downturned margins disposed against said edge faces; a sole-shaped member disposed entirely across the intramarginal part of the insole and having edge faces inset from the edges of the platform; a wrapper having the edges of its upper margin abutting the edge face of said sole-shaped member near the edge of the platform, the wrapper having its lower margin drawn downwardly around said downturned margins and the edge face of the platform and turned inwardly and secured to the margin of the lower face of the platform; a foxing strip having its inner margin superposed upon the upper margin of the wrapper and its lower edge abutting the edge face of the sole-shaped member; the top face of the inner margin of the foxing blank and the bottom face of the upper margin of the wrapper blank being respectively substantially in the upper and lower planes of the sole-shaped member; stitches passing through the insole, the lower

margin of the foxing strip, the upper margin of the wrapper for securing such margins in superposed position and to hold them to the insole; and an upper member having its lower part secured to the upper margin of said strip.

11. Footwear which comprises a platform; a sole-shaped member disposed over the platform and having its edges inset from the edges of the platform; a wrapper having the edges of its upper margin abutting the edge face of said member near the edge of the platform, the wrapper having its lower margin secured beneath the platform; an outsole secured to the lower face of the platform and the lower margin of the wrapper; a strip having its inner margin superposed upon the upper margin of the wrapper and its lower edge abutting the edge face of the sole-shaped member; means for securing the member, strip and wrapper together including stitches passing through the sole-shaped member and an upper member having its lower part secured to the upper margin of said strip.

12. Footwear which comprises a platform having edge faces; an insole superposed on and extending entirely across the platform and having downturned margins disposed against said edge faces; a wrapper having its upper margin adjacent to the insole with the edge of said margin and inset from the edge of the platform, the wrapper having its lower margin drawn downwardly around downturned margins and the edge face of the platform and turned inwardly and secured to the margin of the lower face of the platform; a foxing strip having its inner margin superposed upon the upper margin of the wrapper against the edge of the insole; stitches passing through the insole, the lower margin of the foxing strip, the upper margin of the wrapper for securing such margins in superposed position and to hold them to the insole; a sock lining having its margin disposed over the lower margin of the foxing strip; stitches passing through the insole and the adjacent margins of the wrapper, foxing strip and sock lining.

13. Footwear which comprises a platform having edge faces; an insole stitched and superposed on and extending entirely across the platform and having downturned margins disposed against said edge faces; a sole-shaped member disposed entirely across the intramarginal part of the insole and having its edges inset from the edges of the platform; a wrapper having the edges of its upper margin abutting the edge face of said sole-shaped member near the edge of the platform, the wrapper having its lower margin drawn downwardly around said downturned margins and the edge face of the platform and turned inwardly and secured to the margin of the lower face of the platform; a foxing strip having its inner margin superposed upon the upper margin of the wrapper and its lower edge abutting the edge face of the sole-shaped member; stitches passing through the insole, the lower margin of the foxing strip, the upper margin of the wrapper for securing such margins in superposed position and to hold them to the insole; a sock lining disposed over the sole-shaped member and the lower margin of the foxing strip; stitches passing through the insole and the adjacent margins of the wrapper, foxing strip and the sock lining; and an upper member having its lower part secured to the upper margin of said strip.

14. A process of shoe making which comprises providing an insole member having butt-fastened to the outer edge thereof a foxing strip and a

platform wrapper strip; securing the foxing strip to an upper, placing a platform member beneath said insole member, securing the platform wrapper strip over and beneath the edge of the platform member and securing an outsole to said platform member.
